UNITED STATES PATENT OFFICE.

HENRY B. THOMPSON, OF NEW YORK, N. Y., ASSIGNOR TO LYDIA B. KOCH, OF NEW YORK, N. Y.

CINEMATOGRAPH-TARGET.

1,334,975.

Specification of Letters Patent. Patented Mar. 30, 1920.

Application filed October 17, 1917. Serial No. 196,992.

To all whom it may concern:

Be it known that I, HENRY B. THOMPSON, a citizen of the United States, residing at the borough of Manhattan, city, county, and State of New York, have invented certain new and useful Improvements in Cinematograph-Targets, of which the following is a specification, reference being had therein to the accompanying drawings, which form a part thereof.

My invention relates to cinematograph targets, and more particularly to a type thereof employing a plurality of parallel screens through which the bullet passes before engagement with the back plate. The accuracy of the fire is determined through the illumination of bullet holes by lights arranged rearwardly of said screens.

In this type of target it is customary after marking each shot, to impart relative movement of the screen sections in a manner to prevent a continuance of the light passing through registering bullet openings. It is also customary to provide means, actuated by the back plate or otherwise, for arresting movement of the film in the projector substantially simultaneously with the impact of the bullet with the screen, so as to change the moving image, projected upon the screen, to a still image until the shot has been marked, or for a sufficient interval to permit the marking of the shot.

In some types of targets a multiple screen structure has been formed by a fixed screen section and an intermittently and progressively movable section. In still another type of target, a screen formed of parallel reaches of a continuous strip or web of paper, has been used which web was subject to intermittent, uni-directional movement to obscure the bullet openings. In still another type of target, a continuous web or strip of paper having a uniform continuous travel at low speed has been used. In some types of targets of this character, the projector has been stopped by the closing of a circuit by means of a switch mechanism carried on the firearm itself; in still another type, the circuit has been closed through the agency of a microphone, actuated by the report or concussion, from a firearm, and in still another type, the circuit to the projector has been closed by the displacement of the shield or back plate of the projector from the impact of a bullet therewith. In

all types of targets, it is essential to have the various mechanisms so correlated as to secure accuracy in the timing of the sequence of operations in order to secure accuracy in marking.

In the multiple screen type of targets heretofore used, the parallel screen sections have had only lineal displacement in parallel planes, so that, (this is particularly true with the continuous web targets) it is not at all uncommon for an existing opening in the front screen to come into register with an existing opening in the back screen, thus registering a hit when a shot has not been fired. To avoid this condition, it has been the common practice to impart a considerable movement to the screen so as to have the existing openings in the portion thereof upon which the image is projected remain there as short a time as possible. This, however, has been wasteful of the paper forming the screen. A further objection to the continuous strip form of screen, is that while a fairly high grade paper is required for the surface upon which the image is projected, it is necessary in this type to employ equally high grade paper in the back screen.

By means of a target made in accordance with my invention, I am enabled to utilize a plurality of entirely independent, parallel screens positioned in advance of the shield or back plates, any or all of said screens having imparted thereto slight movement after each stoppage of the projector in two directions so as to minimize the quantity of longitudinal feeding movement of the screen, and thus secure economy in the consumption of the paper forming such screens. By imparting dissimilar movements to different screens, high efficiency in obscuring bullet openings is secured and greater economy in the paper consumption is effected. In securing this result, a plurality of parallel screens are employed, each of which consists of a frame capable in its entirety of physical displacement and carrying a paper supply roll and a re-winding roll for the perforated paper, the paper being ultimately wound from the supply roll to the re-winding roll during the continued operation of the apparatus.

The actuating mechanism for imparting movement to said frames is so constructed as to secure a sufficient dwell of the frames

after the impact of the bullet with the screens to afford ample time for the marker to make a record of the shot. The frame or frames descend by a series of short movements, the paper being wound upon the re-winding roll to secure a gradual change in the exposed portion of the screen, only when each frame approaches the limit of its movement in one direction. By having the 5 different frames descend at different speeds and alternately, the quantity of movement of any screen requisite to obscure a shot opening, is very much reduced; a further reduction being effected by lateral displacement of any screen during a portion of the 10 downward movement of this frame. After each frame has received its maximum movement in one direction, and after a short length of paper has been unwound from the 15 supply, and wound upon the re-winding roll, the direction of the movement of the frame is automatically reversed so that it will be restored to its normal position by a sequence of similar steps. In this manner 20 each of the parallel screen sections is subjected to vertical displacement in its entirety while the screen itself is subjected to lateral displacement with relation to its frame, and to a vertical traveling movement 25 upon its frame, so that with a proper timing in the movements of the different frames, it is possible, if desired to secure six changes of the relative positions of the two parallel screens when used, and by multiplying the number of such parallel screens, 30 the change of position will be a multiple of 3 and the number of screens used. Preferably I employ three such screens.

In conjunction with the movable frames, I 35 employ an actuating mechanism which in the form of the invention shown, and preferably, is controlled by a controlling mechanism operative by the impact of a bullet with a back plate structure consisting of a plurality of independently movable pendulous plates, said actuating mechanism being operative upon the several frames through a timing mechanism by means of which the initial movement of each frame and the 40 duration of such movement is determined. The actuating mechanism is common to all of the frames but the timing mechanism is composed of a plurality of similar mechanisms each of which is operative with relation to its particular frame. Associated 45 with the timing mechanisms are a plurality of reversing mechanisms by means of which the direction of each frame will be automatically reversed as it reaches either its 50 uppermost or its lowermost position. In apparatus of this character, it is necessary to combine great strength of structure with comparative delicacy in the controlling and timing mechanisms to insure reliability in 55 their operation as well as that rapidity

necessary by reason of the desirability of permitting the discharge of firearms at the target in rapid succession.

In a machine made in accordance with my invention, the actuating mechanism is so 70 constructed as to permit of its release by the controlling mechanism when an impulse is imparted to any of the back plates by the impact of a bullet therewith, the proportionate weight of the several parts and their 75 operative relation being such as to secure the automatic restoration of the back plates, and the controlling mechanism to normal after each actuation thereof, with sufficient 80 rapidity to insure the repeated actuation of said controlling mechanism under the influence of bullets striking the target in quick succession.

The necessity for exactitude in the timing of the different operations to secure accuracy when the apparatus is rapidly actuated in quick succession requires nicety 85 in the counterbalancing of the various frames.

It is preferable to use the controlling 90 mechanism for automatically closing and opening the circuit to the projector to convert a moving image to a stationary image and vice versa.

In order to secure a dwell of the stationary image upon the screen, I provide a controller or brake mechanism which may be so set, under the control of the operator as to retard the closing of the circuit to the projector or to prevent the closing of the circuit 100 in the event that the marker desires to more closely inspect the target. This controlling of the circuit by the operator is entirely mechanical, in the form of the invention shown, and is highly desirable for 105 use in the event of the target being used for match purposes. When the target is used merely as an amusement device, however, the necessity for such a brake mechanism is not present since the machine may 110 be so designed as to insure perfect timing in the opening and closing of this circuit.

In addition to using said controller or brake mechanism for timing the closing of the circuit, this mechanism may also be used 115 to modify the normal operative effect of the timing mechanism for the several frames to prevent the premature movement of any screen when the opening of the circuit to the projector is prevented or retarded, thus 120 bringing the projector controlling mechanism and the timing mechanism in synchronism with each other.

To simplify the structure of the apparatus, the lateral displacement of the 125 screens is effected by means of a sequence of contacts engaging the ends of the paper supply and the re-winding rolls, thus causing the movement of the frame to result in this lateral displacement.

Throughout the apparatus the construction and relation of parts is such as to reduce, as much as possible, the power required to operate the various parts and to have the motive power for the controlling mechanism, the main actuating and timing mechanism and the reversing mechanism entirely independent, one of the other. The construction and arrangement is also such as to permit the operation of the machine with substantially uniform power at all times. I also preferably so construct the back plate or shield mechanism as to divide it into a plurality of units each consisting of a plurality of rows of plates, so suspended as to utilize the moving inertia of a plurality of said plates when a bullet impacts upon any of them, in actuating the controlling mechanism, while preserving the relation of each plate and said controlling mechanism so that it will be operative upon said controlling mechanism at all times.

The invention consists in the novel features of construction and combination of parts hereinafter set forth and described and more particularly pointed out in the claims hereto appended.

Referring to the drawings:—

Figure 1 is a front elevation of a target embodying my invention, successive screens being broken away and the front of the target frame being removed to disclose the various mechanisms;

Fig. 2 is a vertical section of the target; Fig. 3 is a detail assembled view of the controlling mechanism;

Fig. 4 is a detail view of the escapement pallet and a portion of the escapement wheel;

Fig. 5 is a detail view of the switch mechanism;

Fig. 6 is a detail view of the brake mechanism for controlling said switch mechanism;

Fig. 7 is a detail view of the timing mechanism and the reversing mechanism operating thereon;

Fig. 8 is a detail view of the construction by which lateral movement is imparted to the various paper rolls and for actuating the re-winding rolls; and

Fig. 9 is a plan view of the guides for the various frames.

Like letters refer to like parts throughout the several views.

In the embodiment of my invention shown in the drawings, the front of the screen is provided with a frame A, the sight opening of which defines the exposed area of the front screen, upon which the image, either fixed or moving, is projected. Adjacent the frame A in the fore part of the main target structure, are three independent, vertically reciprocatory frames B—C—D. Each of said reciprocatory

frames has at the top thereof a paper supply reel and at the bottom thereof a paper re-winding reel. The top reel carried by the frame B is indicated at B' and the bottom reel at B²; the top reel carried by the frame C is indicated at C' and the re-winding reel at C²; and the top reel carried by the frame D is indicated at D' and the re-winding reel at D². Adjacent the top and bottom of the frame A are guide rollers A'—A' about which the paper strip passes from the reel B' to the reel B²; guide rollers A²—A² about which the strip of paper passes from the reel C' to the reel C², and guide rollers A³—A³ about which the strip of paper passes from the reel D' to the reel D², these various rollers being so positioned as to hold each strip of paper taut across the sight opening during movement of the several frames, and to space the separate strips apart sufficiently to prevent such frictional engagement as might tend to wrinkle any of the strips of paper or interfere with the free movement thereof.

Rearwardly of the frames B—C—D is a back plate or shield structure having the two-fold function of arresting a bullet and utilizing the force of the impact thereof for actuating the controlling mechanism for the various mechanisms incidental to the operation of the machine.

Each of the back plate units above referred to comprises nine metal plates 1, arranged in three parallel rows of three each. The adjacent plates are arranged upon different planes and the dimensions of these plates are such as to overlap in a manner to insure the full force of the impact of the bullet being imparted to one plate. Each plate is mounted upon a rearwardly projecting frame 2 pivotally supported from the two pairs of parallel suspension bars 3 which in turn are pivotally connected at their upper ends with suitable brackets, thus permitting each of the plates 1 to swing freely. By having each plate positioned forwardly of the suspension bars 3, the center of gravity of each pendulous plate will be rearwardly of the points of suspension of said bars so that the plate will have a normal thrust away from the frame A.

Rearwardly of each horizontal row of plates 1 is a rock shaft 4 carrying a plurality of crank arms 5 projecting toward and into engagement with the supporting frame 2 of the plate 1. Slidably mounted in the frame work of the back plate structure, are vertically extending rods 6 each provided with a plurality of shoulders or sockets 7 co-operating with a short crank arm 8 carried by each of the rock shafts 4. By this construction a movement of any of the rock shafts 4 will raise said rod 6.

Also mounted in the frame work of the back plate structure, and common to all of

the back plate units, is a rock shaft or verge 9 by means of which the movement of said vertical sliding rod under the control of any of the rock shafts 4 operative thereon, will 5 be utilized for actuating the escapement mechanism for releasing the various mechanisms operative to control the projector and the movement of the various screens.

Carried by the rock shaft or verge 9 is 10 a crank arm 10 bearing upon a shoulder 11 upon the vertically sliding rod 6.

The mechanism heretofore described constitutes the controlling mechanism, the purpose of which is merely to cause the impact 15 of the bullet with any portion of the back plate to result in the automatic actuation of other mechanisms of the apparatus.

The various frames B—C—D are actuated from the same source of power which 20 in the form of the invention shown consists of a shaft 12 actuated through a drum 13.

The shaft 12 is connected by the chain and sprocket mechanism 14 with a shaft 15 which shaft in turn transmits power by the chain and sprocket mechanism 16 to a shaft 17 which extends completely across the machine. Mounted upon the shaft 15 is an escapement wheel 18 coöperating with 30 which is a pallet mechanism carried by the rock shaft or verge 9.

Said pallet mechanism comprises lugs 19 carried by the shaft 9 having pivoted thereto the stops 20 adapted to alternately 35 engage the teeth of the escapement wheel 18. The two stops 20 are pivoted to the opposite ends of a rock arm 21 to facilitate the engagement and disengagement of said stops with the teeth of the escapement 40 wheel. In the form of the invention shown the teeth of the wheel 18 are arranged on centers 10° apart so that upon the disengagement of each stop said wheel will advance 5°. Since the shaft 9 with each actuation 45 of the controlling mechanism will turn first in one direction and then in the other, the construction above referred to will divide the operative moment of all of the mechanisms controlled by said shaft 50 into two succeeding steps.

The mechanism for imparting movement to the several frames B—C—D is the same for each frame, the mechanism for different frames being differently set and of different 55 dimensions so as to secure not only a variance in timing of the movement of the several frames, but also of the quantity of such movement. The construction and operation of each of these mechanisms is the same with 60 the exception above noted and a description of but one of them will be entered into. This mechanism comprises a double ratchet wheel 22 idly mounted upon a shaft 23 and carrying a sprocket 24 about which passes a 65 chain 25, the opposite ends of which are

secured to the top and bottom side rails of the frame to be actuated thereby. Coöperating with the ratchet wheel 22 are a plurality of pawls 26 and 27 mounted upon a reciprocating support 28. This support in 70 turn is mounted upon an eccentric 29 carried by a shaft 30 operatively connected with the shaft 17 by the chain and sprocket mechanism 31. To provide that dwell after the actuation of the controlling mechanism necessary 75 to cause the shot holes to remain in register for a sufficient interval to determine the accuracy of the fire, it is essential that the pawls 26 and 27 shall not be operative upon the ratchet 22 during the initial movement of the support 28. To avoid any possibility of a premature engagement of either of said pawls with said ratchet, I provide a double, inclined shield 32 which will serve to hold either of said pawls out of engagement 80 with said ratchet until said support has had a certain predetermined reciprocating movement. The double pawl mechanism and double shield are provided, since in the operation of the machine it is essential 85 to impart movement to said ratchet wheel in opposite directions during different intervals in the operation of the apparatus.

The support 28 for the pawls 26 and 27 is under the control of a reversing mechanism 90 by means of which the operative relation of the pawls 26 and 27 and the ratchet 22 is automatically determined.

The reversing mechanism above referred to comprises a plurality of levers 33—34 100 having movement with their frame, similar arms of each of said levers being pivotally connected by a tie rod 35.

Extending parallel with the side of the vertically moving frame is a guide rod 36 105 supported in any desired manner from the frame A, rearwardly of its associated frame B, C or D, and having adjustably mounted thereon stops 37 and 38. Said rod is of a length to permit the stops 37 and 38 to be 110 adjusted within the maximum vertical movement of said frame B, C or D. Slidably mounted upon said guide rod 36 is a traveling block 39, the blocks 37—38 limiting the reciprocating movement of the block 39 in 115 either direction. Encircling the tie rod 35, with their opposite ends seated respectively upon the traveler 39 and the collars 40 and 41 upon the said rod 35, are coiled springs 42 and 43 adapted to alternately accumulate 120 sufficient energy during the movement of the frame in either direction to supply the power necessary to automatically set the mechanism for reversing the direction of this movement. The lever 33 is mounted in the 125 bracket 44 and the lever 34 is mounted in the bracket 45. The brackets 44 and 45 are forked (see Fig. 7) the rod 36 and stops 37—38 being adapted to pass between the arms thereof during the vertical movement of 130

the movable frame. The levers 33 and 34 are provided respectively with a spring pressed latch 46-47 whereby each of the levers will be held against movement during the interval when the spring 42 or 43 is being tensioned. The latches 46-47 are pivotally mounted upon the levers 33-34 respectively and are spaced away therefrom to afford clearance for the actuating rods 50-51, this clearance being sufficient to afford passage-way for the blocks 52-53 upon said rods. One end of each latch 46-47 is projected toward its associated lever, as indicated in dotted lines upon latch 47, Fig. 7, which projection defines the pivotal movement of said latch in one direction, the spring acting thereon limiting this movement in the other direction. The springs acting upon said latches serve merely to hold the latches in engagement with their coöperating keepers, while the spring 42 or 43 is being tensioned, and thus resist the stresses from said spring until the latch is positively released against the tension of its spring by engagement with the block 52 or 53.

The brackets 44 and 45 each have a keeper with which the latch members 46 and 47 respectively coöperate said members normally projecting perpendicularly to each other so that these latch members will alternately engage their respective keepers. The said keepers are indicated at 48 and 49 respectively. Carried by the traveler 39 are trip rods 50 and 51 each of which has adjustably mounted thereon a contact block 52-53, adapted to engage the latch member 46-47 when movement has been imparted to the traveler 39 to tension either of the springs 42-43 and disengage said latch member from said block to permit the oscillations of the levers 33-34 through the movement of the tie rod 35 under the influence of said springs. The rod 50-51 respectively passes between its associated lever 33-34 and the latch 46-47 carried thereby. These rods, as shown, are pivotally mounted upon the traveler block 39, although this is not essential. These rods are of a length so that they will always extend beyond the brackets 44-45 and be positioned between the pivots of the latches 46-47 and the pivot of said lever when said latches engage their respective keepers. The rod 51 is of a length so that when its movable frame is in the lowermost position, the end thereof will be above the pivot of the latch 47, thus permitting the unobstructed movement of said lever and said latch. Carried by the outer ends of the arms 33-34 is a guide frame 54 having a way therein adapted to receive a roller 55 carried by a link 56 connected with the extension 57 upon the support 28. One of the bars of the guide frame 54 is extended, as at 58, 65 so as to limit the downward movement of

the said guide frame by engagement with the end of the bracket 44. The function of the reversing mechanism heretofore described is merely to rock the support 28 in a manner to bring the pawls 26 and 27 carried by said support, successively into the operative relation to the ratchet wheel 22.

Each frame is provided with two reversing mechanisms like that above described arranged upon the opposite sides of the machine.

The blocks 37 and 38 are adjustably mounted upon the guide rod 36 so as to permit exactitude in the regulation of the timing of the operative engagement of the stops 52-53 with the latch members 46-47, said stops being adjustable to facilitate the assembly of the machine and bring the reversing mechanisms operative upon opposite sides of the frame into complete synchronization.

To prevent a too rapid completion of the cycle of operation under the control of the main actuating mechanism after the impact of a bullet with the screens and afford a dwell prior to the movement of any of the frames, I provide a controller mechanism which will permit the free oscillation of the rock shaft or verge 9 in one direction and check its return movement. In conjunction with this controller or brake mechanism, I also provide means whereby the operative effect thereof may be modified by an attendant, so as to increase the resistance to the movement of said rock shaft or verge or diminish said resistance even to a degree where the controller or brake mechanism will be totally inoperative upon said shaft.

This controller or brake mechanism comprises a pivoted arm 59 carrying a roller 60. Acted upon by a wedge 61 is a pivotal block 62 between which and the arm 59 is interposed a spring 63. The wedge 61 is actuated by the projection 64 carried by the rock shaft or verge 9. Mounted upon the main frame of the machine, is a roller 65. Adjacent the shaft 9 is a rock lever 66, one end of which is connected by the link 67 with a crank 68 carried by the rock shaft or verge 9. The other end of said lever is connected with a bar 69 by means of a link 70 so as to permit a vertical reciprocation of said bar 69. Carried by the main frame of the machine opposite to and spaced away from the arm 59 is a pivoted block 71 carrying a roller 72, the bar 69 being engaged by the rollers 59-65 upon one side thereof and 72 upon the other side thereof. The block 71 is acted upon by a cam 73 adapted to be turned by means of the arm 74 so as to force the roller 72 toward the rollers 60-65 or permit said roller to recede therefrom.

The first movement of the shaft 9 will be such as to cause the crank 68 to move down-

wardly. It is apparent that prior to such initial movement the wedge 61 will permit the block 62 to recede from the arm 59 in a manner to relieve said arm from such pressure as will cause the rollers 60—65 and 72 to exert a clamping action upon the bar 69; but that toward the end of the downward movement of the crank 68, said wedge will have forced the roller 60 into such engagement with the bar 69 as to materially retard the movement thereof until the reverse movement of the shaft will have been sufficient to relieve the pressure upon said rod so as to permit it to slide freely between the several rollers engaging same. By changing the relative positions of the cam 73 and block 71 the extent of the clamping action above referred to may be regulated. Any suitable means which will permit the movement of the arm 74 from a point remote from the target mechanism may be employed.

In the form of the invention shown, I employ a projector, the feeding mechanism for which is connected with the power for driving same through a clutch which is normally set to transmit power to said feeding mechanism; which clutch is adapted to be released through the medium of an electro-receptive device included in a normally open circuit. Hence, it is essential, when arresting the operation of the projector substantially simultaneously with the impact of a bullet with the screen, to automatically close the circuit of said electro-receptive device upon the initial movement of the controlling mechanism of my target apparatus. To secure this result, I preferably employ a contact switch of special construction, by means of which the circuit to said electro-receptive device will be closed substantially simultaneously with the initial movement of the rock shaft or verge 9 and will be held closed until said rock shaft has returned substantially to normal. In the accompanying drawings, I have not illustrated the projector itself, since such is immaterial to my present invention which relates to the target mechanism itself.

The switch above referred to comprises a fixed contact 75, suitably insulated from the main frame of the target adjacent the rock shaft or verge 9. Loosely mounted upon said shaft or verge is an arm 76 carrying a contact 77 movable therewith, insulated therefrom and adapted to be brought into engagement with the contact 75. Keyed or otherwise secured to the shaft or verge 9 is an arm 78 adapted to impart movement to the arm 76 through the medium of a spring 79. In this manner the initial movement of the arm 78 will impart such movement to the arm 76 as is necessary to bring the contacts 75 and 77 into electrical engagement with each other, subsequent move-

ment of the arm 78 being independent of that of the arm 76 and against the tension of the spring 79. It is essential, however, to provide means whereby the reversal of the movement of the arm 78 will separate the contacts 75 and 77 which means in the form of the invention shown comprises the tie bolt 80 passed through openings in the same arms 76 and 78. To permit adjustment as to the time of separation of said contacts, I provide the bolt 80 with an adjustment nut 81 by means of which the interval during which the circuit remains closed may be varied.

It must be understood that all of the operations heretofore referred to occur substantially simultaneously the complete cycle of operations requiring but a fraction of a minute, particularly under conditions of use where bullets impact with the screen in rapid succession.

Each reel of each pair of rollers B'—B², C'—C², and D'—D² is suitably mounted upon its frame B—C—D in a manner to permit lateral movement thereof. Each of said reels is normally centered in relation to its frame by means of the springs 82—83 acting upon opposite ends thereof. Carried by the main structure of the machine toward the top thereof and in the path of movement of the projecting ends of the paper supply reel are two sets of contact rolls 84—85, the rolls of one set being arranged on different horizontal planes from, or staggered in relation to, those of the other set. Toward the bottom of the target structure are similarly arranged sets of rolls 86—87. The rolls of the sets 84—86 and 85—87 are so set as to simultaneously act upon the paper supply reel at the top of the frame and the re-winding reel at the bottom thereof so as to impart a parallel movement to the paper extending from one reel to the other as the movement of the frame causes said reels to engage said rolls.

While this lateral shifting mechanism for the paper supply and re-winding reels is duplicated for each frame the rolls for different frames may be set on different levels, if desired, so as to vary the moment of lateral movement of the reels upon different frames.

The re-winding roll of each frame is provided with ratchet wheels 88 co-operating with which is a pawl 89 carried adjacent the bottom of the main target structure. Each pawl 89 is preferably carried upon a lever 90 one end of which projects toward the re-winding reel so that with the gradual increase in the diameter of the paper upon said re-winding reel, the pawl will be advanced so as to secure a gradual reduction of the circumferential movement of the reel in a manner to insure a substantially uni-

form lineal movement of the paper web or strip. Since the quantity of feeding movement of the rewind mechanism results from the interval during which the pawl 89 is in engagement with its co-operating ratchet wheel 88, it is apparent that by raising said pawl by means of the lever 90, as a result of the engagement of the roll of paper upon the rewind reel, it will shorten this interval, thus gradually reducing the quantity of rotative movement of said reel with a given movement of the frame carrying same. This reduced rotative movement of the reel will be in proportion with the diameter of the roll of paper thereon.

Each of the reels carried by each frame is provided with a friction device such as that indicated at 91 to prevent overrunning of any reel and insure the paper being held perfectly taut between the paper supply reel and the re-winding reel.

Each of the frames B—C—D is provided with a counterweight 92 acting upon each side thereof through the flexible connection 93.

Carried adjacent the top and bottom and upon the opposite sides of the main structure of the machine is a fitting 94 having mounted thereon anti-friction rollers 95—96—97—98 and 99. The roller 95 engages one edge of the frame B and the rollers 96—97 engage opposite sides of the extension 100 carried by said frame, thus preventing any substantial swaying of said frame while permitting it to slide freely. The frame C is engaged by a roller 101 carried by the frame B and an extension 102 upon said frame C is engaged by the roller 98 and by a roller 103 carried by the extension 100. An extension 104 carried by the frame D is engaged by the roller 99 and by a roller 105 carried by the extension 102 of the frame C. In this manner the various frames B—C—D are properly guided in their vertical reciprocation and are held apart to prevent any interference in the free movement thereof by reason of frictional engagement between the different frames or the extensions thereof. The guide mechanism above referred to affords a simple and compact anti-friction guide permitting the various frames to be mounted in close juxtaposition without likelihood of interference.

The paper web carried by the frame B is indicated at 106; that carried by the frame C at 107; and that carried by the frame D at 108. The lamp for illuminating the bullet openings through the several screens is indicated at 109. If desired this lamp may be included in the circuit to the electro-receptive device controlling the clutch mechanism for the projector so that simultaneously with the stoppage of the projector the lamp 109 will be lighted, but will not consume current at other times.

The operation of the herein described mechanism is substantially as follows:—

In describing the operation of the target, a complete cycle of operation resulting from the impact of one bullet with the shield or back plate will be first described in detail, and the relative operations of different parts upon impacts of succeeding bullets will then be described.

Assuming that a moving image is projected upon the screen 106, and a shot is fired, the bullet will pass through each of the screens 106—107—108 leaving three registering openings of comparatively small dimensions, before it impacts with one of the pendulous plates 1. As the bullet impacts with said plate, the force of this impact, added to the normal thrust of the frame 2 upon the crank arm 5 with which it engages, will rock the shaft 4 and cause all of the crank arms 5 carried thereby to recede from their respective plates with the two-fold effect of adding the load of these other plates to the power imparting movement to the rock shaft and cause all of the plates to remain in constant engagement with their respective arms 5. As the shaft 4 rocks, the single crank arm 8 carried thereby will raise the rod 6 and thus impart a direct movement to the rock shaft or verge 9, by reason of the relation of the crank arms 8 upon different shafts 4 to the rod 6.

Upon the direct movement of the rock shaft or verge 9 under the control of a back plate 1, the pallet mechanism will be actuated to withdraw one of the stops 20 in a recessional arc from its engagement with the escapement wheel 18, thus permitting power from the drum 13 to be applied to the mechanisms actuated thereby.

At the same time the arm 78 will be thrust toward the arm 76 carrying the contact 77, forcing said contact into electrical engagement with the contact 75 through the medium of the spring 79 which spring after said contact is made will yield to permit the continued movement of the arm 78 while holding said contacts in engagement with each other. By the closing of the circuit controlled by the contact 75—77 with the initial movement of the shaft or verge 9, the moving image projected upon the screen 106 will be converted to a fixed image substantially simultaneously with the impact of a bullet with the screen. At the same time the closing of this circuit may be used to close the circuit to the light 109 rearwardly of the screen, so as to cause this light to illuminate the registering bullet openings in the screen 106—107—108.

Upon the rotation of the shaft 12 due to the release of the escapement wheel 18, power will be transmitted through the chain and sprocket mechanisms 14—16—31 to the shaft 30, the relative dimensions of the va-

rious sprocket wheels being such that a 5° movement of the escapement wheel will impart a movement of 60° in arc to the said shaft 30. This movement of the shaft 30 will reciprocate the support 28 so as to bring the pawl 26 or 27 into engagement with the ratchet wheel 22 without, however, imparting any movement thereto, the shield 32 holding said pawl out of engagement with the ratchet wheel at all times prior to the substantial completion of this first movement or step. Hence, it will be observed that the operative effect of the direct oscillation of the rock shaft or verge 9 will be to close the circuit for stopping the projector and to illuminate the back of the screen when desired; and to set the timing mechanism preparatory to the actuation of at least one of the screens for the purpose of obscuring the openings passing through three screens; and that no movement will be imparted to any of said screens during this brief interval.

The first direct movement of the shaft 25 or verge 9 will through the arms 68, link 67, rocking lever 66 and link 70 impart a downward thrust to the bar 69, and a reciprocatory movement to the wedge 61 through the projection 64; so that during 30 this downward movement there will be little or no braking action upon the bar 69. Toward the end of this movement, however, said bar will be thrust toward the friction roller 72 by the arm 59, spring 63 and block 62 by reason of the movement of the wedge 61; so that said bar will be lightly clamped between the rollers 60-65 and 72 in a manner to momentarily retard a return movement of the rocking lever 66 and the 40 rock shaft or verge 9.

All of the movements heretofore described occur substantially simultaneously with the impact of a bullet with the screen. Immediately thereafter the dead load of the bar 6 upon the crank arm 10, will tend 45 to impart a return movement to said rock shaft or verge 9, which movement will be sufficiently resisted by the brake mechanism acting upon the bar 69, and during the initial return movement to prolong the dwell slightly until the wedge 61 has been withdrawn sufficiently to relieve the braking action upon said bar 69 and permit a more rapid movement of the said shaft or verge 9. Upon this return movement, the other stop 20 is withdrawn in a recessional arc from the escapement wheel 18 permitting the said wheel to turn a further 5° in arc, thus causing the shaft 30 to turn a further 60° in arc to complete the first 60 cycle of operation.

As the shaft 30 makes this further movement, it will impart further reciprocatory movement to the support 28, thus turning 65 the ratchet wheel 22 sufficiently to cause

the sprocket wheel 24 and chain 25 to impart a short lineal traverse to the frame controlled thereby.

Since the full movement of a frame may be secured by a 120° movement in arc of 70 the shaft 30, it is apparent that where three screens are used the eccentrics 29 may be so set with relation to each other that the different frames B-C-D may be successively actuated either in the same or in opposite directions according to the setting of said eccentrics. It is also apparent that by having the sprocket wheels 24, imparting movement to the different frames of different diameters, the quantity of lineal traverse of different frames will also be varied. 75

Each of the frames B-C-D will either descend or ascend by a series of short steps, until it has completed the maximum lineal traverse in each direction. 80

During this traverse the projecting ends of the reels B'-B², C'-C² and D'-D² will engage the different rolls of the sets 84 and 86, and 85-87 alternately, thus imparting a lateral movement to the webs 106-107 or 90 108 during this traverse, and not only bringing the registering bullet opening in the screens out of alignment as to a horizontal plane, but also out of the alignment as to a vertical plane. While the vertical movement 95 of the screens results from a corresponding movement of the frame carrying same, the lateral movement of said screens results from a movement of the reels over which the paper strip passes, as a result of the 100 engagement of first one end of said reels by rolls of the sets 84 and 86, and the alternate engagement of the other end thereof by rolls of the sets 85 and 87. The rolls of the sets upon one side being upon a different horizontal plane from the rolls of the sets upon the other side, affords clearance 105 for the movement of said reels, and causes the movement above referred to, against the tension of the springs 82 and 83. 110

As the frame approaches the limit of its downward movement, the pawl and ratchet mechanism 88-89 will draw a short section of the paper web or strip from the paper supply reel and wind it upon the paper rewinding reel. 115

The quantity of movement of the paper strip or wedge 106-107-108 required to prevent the light rays from passing through registering bullet openings is very small so 120 that the various movements heretofore referred to are short.

During the lineal traverse of any frame, the brackets 44-45 and the levers 33-34 and the parts appurtenant thereto carried 125 by said frame will travel with said frame until the traveler 39 engages one of the stops 37-38 according to the direction of movement of the frame, without varying the relative position of parts. After the en- 130

agement of said traveler with either of said stops, one of the springs 42-43 will be tensioned to store up sufficient energy to actuate the reversing mechanism. Assuming that the parts are in the position shown in Fig. 7 with the latch member 46 engaging the keeper 48 and the guide 54 projected to the full extent, the downward movement of said frame will bring the traveler 39 into engagement with the stop 38 and by a continued movement of the frame, the spring 42 will be tensioned. During the movement required to tension this spring, the latch member 46 will be brought into engagement with the contact block 52 until ultimately it disengages it from the keeper 48, thus releasing the lever 33 and permitting the spring 42 to swing said lever 33 and the lever 34 about their respective pivots, forcing the frame 54 downwardly and toward the frame A, until the extension 58 engages the end of the bracket 44 and the latch 47 engages the keeper 49. During the tensioning of the spring 42, the tendency of the lever 33 to move will be resisted by the spring acting upon the latch member 46. The engagement of the latch member with the block 52, will, however, overcome the tension of the latch spring, and rock the latch member until it clears its keeper 48. As the lever 34 is swung downwardly, the pivot of the latch member 47 will pass below the end of the rod 51 and said latch member will be moved about its pivot until the end thereof clears the keeper 49, gravity being relied upon to impart sufficient return movement thereto to cause it to engage said keeper and the spring acting upon said latch. Thereafter the action of these parts upon the reversal of movement of the brackets 44-45 will be as described with relation to the keeper 46. This movement of the frame 54, will, through the link 56, rock the support 28 about its eccentric so as to bring one pawl as 27 out of the operative relation to the ratchet 22 and bring the other pawl 26 into such relation thereto as will cause the subsequent reciprocation of said support under the control of its eccentric to actuate the ratchet wheel 22 in the opposite direction, and cause the next actuation of said support to raise the frame B. The slot in the guide frame 54 will permit said frame to have vertical traverse with relation to the roller 55 in either direction. By pivotally connecting the frame 54 with the levers 33-34 as shown, said frame 54 will always be in a vertical position irrespective of the position of said levers. As the frame carrying the brackets 44-45 ascends, the operations above described will be reversed, the traveler 39 engaging the stop 37, the spring 43 being tensioned thereafter and the collar 53 by its engagement with the latch

member 47 releasing the said latch member when the frame B has reached the limit of its movement, permitting the expansion of the spring 43 and the restoration of the various parts to normal, as shown in Fig. 7 of the drawings. 70

The operative effect of the re-winding mechanism is apparent from the foregoing description, it being merely necessary to point out that the paper strip or web is not re-wound with each actuation of the frame but only after a sequence of such operations. 75

Toward the end of the return movement of the rock shaft or verge 9, the pressure of the arm 78 upon the spring 79 will be relieved and ultimately the arm 77 will be actuated through the bolt 80 and the nut 81 in a manner to separate the contact 75-77 so as to convert the still image upon the projector to a moving image substantially simultaneously with the completion of the movement of the web. 80-85

The timing mechanism and the reversing mechanism associated therewith are duplicated upon opposite sides of the main structure by reason of the desirability of applying the power to move the screen frames to opposite sides thereof. 90

While the operative effect of the timing mechanism is the same upon each frame, it is unnecessary to have more than one frame move at a time. In fact it is preferable to have only one frame move at a time. By having the frames move successively in any desired sequence the quantity of feeding movement required of any screen, with a given number of shots, will be reduced to a minimum. The lateral movement of the screens will cause the strip or web to descend in a zig-zag course which will reduce the quantity of lineal traverse necessary to secure the desired operative effect in obscuring the bullet openings. 95-105

As the rock shaft or verge 9 oscillates in returning to normal, the rod 6 will descend through gravity restoring any of the rock shafts 4 which may have been actuated to their normal position. The different leverages of the arms 5 and 8 carried by said shaft, results in the application of sufficient power to restore the frames 2 which may have been displaced, to their normal forward position. 110-115

If two bullets strike the plate substantially simultaneously there will be one actuation of the controlling and the timing mechanism; but by reason of the employment of the escapement mechanism herein described, in the event that succeeding bullets strike the plate in rapid succession and before the plates have fully returned to their normal positions, the constant engagement of each plate with its arm 5 will immediately reverse the direction of movement 120-125-130

of the rock shaft or verge 9 and cause a succeeding operation of the controlling mechanism and also of the timing mechanism.

The elapsed time required to complete the cycle of operations above referred to is so short as to permit the discharge of shots at the target in rapid succession. In fact by relieving the bar 69 from all pressure from the roller 72, the various operations will be 10 in such rapid succession as to be substantially simultaneous.

Even though the shots strike the target in rapid succession, the construction of the controlling mechanism and the timing mechanism and other mechanisms in the machine are such that there can be no interference between, or any loss of synchronism in, the operation of the various mechanisms.

In a machine made in accordance with my 20 invention, it is merely necessary that the front strip or web 106 be made of high grade paper, the strips or webs 107—108 being of a lower grade of paper.

It will be observed that the power for 25 moving the several screens is derived from the drum 13 and shaft 12 and that this power is entirely independent of the motive power for restoring the various plates and the rock shaft or verge 9 to normal. The 30 said controlling mechanism is restored to normal by the weight of the rods 8 and the direct movement of said rock shaft or verge 9 as heretofore stated, results from the over-balancing of the plates 1 from the force of 35 the impact of the bullet therewith coupled with the differential of leverage of the arms 5 and 8.

While both vertical and lateral movement 40 of the screens is highly desirable in that it secures a more rapid securing of the registering bullet openings with a relatively small lineal traverse of the frame, it is apparent that if desired the direction of movement of the frame may be limited to the 45 vertical lineal movement.

It is not my intention to limit the invention 50 to the precise details of construction shown in the accompanying drawings, it being apparent that such may be varied without departing from the spirit and scope of the invention.

Having described the invention what I claim as new and desire to have protected by Letters Patent is:—

55 1. A cinematograph target embodying therein a back plate comprising a plurality of independently movable sections, a plurality of independently movable frames, a screen carried by each of said frames, means 60 whereby lineal traverse is imparted to said frames successively and controlling means for said last named means adapted to be operated by the movement of any of said sections of said back plate to release said last

named means to impart movement to said frames.

2. A cinematograph target embodying therein a back plate comprising a plurality of independently movable sections, a plurality of independently movable frames, a screen carried by each of said frames, means whereby lineal traverse is imparted to said frames successively, controlling means for said last named means adapted to be operated by the movement of any of said sections of said back plate to release said last named means to impart movement to said frames, and means actuated by the said controlling means for stopping the projector substantially simultaneously with the impact of a bullet with any back plate section.

3. A cinematograph target embodying therein a back plate comprising a plurality of independently movable sections, a plurality of independently movable frames, a screen carried by each of said frames, means whereby lineal traverse is imparted to said frames successively, an automatically acting reversing mechanism whereby the direction of said traverse will be varied at predetermined intervals and controlling means for said last named means adapted to be operated by the movement of any of said sections of said back plate to release said last named means to impart movement to said frames.

4. A cinematograph target embodying therein a back plate comprising a plurality of independently movable sections, a plurality of movable frames, a screen carried by each of said frames, means whereby slight vertical lineal traverse is imparted to said frames successively, means whereby lateral movement is imparted to said screens during said lineal traverse, and controlling means for said last named means adapted to be operated by the movement of any of said sections of said back plate to release said last named means to impart movement to said frames.

5. A cinematograph target embodying therein a back plate comprising a plurality of independently movable sections, a plurality of independently movable frames, a paper supply reel and a re-winding reel carried by each of said frames, means whereby said re-winding reel is automatically actuated at predetermined intervals, means whereby lineal traverse is imparted to said frames successively and controlling means for said last named means adapted to be operated by the movement of any of said sections of said back plate to release said last named means to impart movement to said frames.

6. A cinematograph target embodying therein a back plate comprising a plurality of independently movable sections, a plural-

ity of independently movable frames, a paper supply reel and a re-winding reel carried by each of said frames, means whereby said re-winding reel is automatically actuated at predetermined intervals, means whereby slight vertical lineal traverse is imparted to said frames successively, means whereby lateral movement is imparted to said reels during said lineal traverse, and controlling means for said last named means adapted to be operated by the movement of any of said sections of said back plate to release said last named means to impart movement to said frames.

15 7. A cinematograph target embodying therein a back plate comprising a plurality of independently movable sections, a plurality of independently movable frames, a screen carried by each of said frames, means whereby lineal traverse is imparted to said frames successively and controlling means for said last named means adapted to be operated by the movement of any of said sections of said back plate to release said last 25 named means to impart movement to said frames, comprising an escapement wheel included in the means for imparting movement to said frames, an oscillatory rock shaft or verge, a pallet carried thereby and 30 operatively engaging said escapement wheel, and operative connections between said verge and each of the sections of said back plate.

8. A cinematograph target embodying therein a back plate comprising a plurality of independently movable sections, a plurality of independently movable frames, a screen carried by each of said frames, means whereby lineal traverse is imparted to said frames successively and controlling means 35 for said last named means adapted to be operated by the movement of any of said sections of said back plate to release said last named means to impart movement to said frames, comprising an escapement 40 wheel included in the means for imparting movement to said frames, an oscillatory rock shaft or verge, a pallet carried thereby and operatively engaging said escapement wheel, and operative connections be- 45 tween said verge and each of the sections of said back plate, said pallet consisting of lugs carried by said rock shaft or verge, a stop pivotally mounted upon each of said lugs, and a rock arm connecting said stops.

55 9. A cinematograph target embodying therein a back plate comprising a plurality of independently movable sections, a plurality of independently movable frames, a screen carried by each of said frames, means whereby lineal traverse is imparted to said frames successively, controlling means for 60 said last named means adapted to be operated by the movement of any of said sections of said back plate to release said last

named means to impart movement to said frames, comprising an escapement wheel included in the means for imparting movement to said frames, an oscillatory rock shaft or verge, a pallet carried thereby and operatively engaging said escapement wheel, 70 and operative connections between said verge and each of the sections of said back plate, and a brake mechanism operative upon said rock shaft or verge.

10. A cinematograph target embodying 75 therein a back plate comprising a plurality of independently movable sections, a plurality of independently movable frames, a screen carried by each of said frames, means whereby lineal traverse is imparted to said frames successively, controlling means for 80 said last named means adapted to be operated by the movement of any of said sections of said back plate to release said last named means to impart movement to said frames, comprising an escapement wheel included in the means for imparting movement to said frames, an oscillatory rock shaft or verge, a pallet carried thereby and operatively engaging said escapement 85 wheel, and operative connections between said verge and each of the sections of said back plate, and a brake mechanism operative upon said rock shaft or verge comprising a reciprocatory bar operatively connected 90 with said rock shaft or verge, a plurality of rollers disposed on opposite sides of said bar, a movable support for one of said rollers and means actuated from said rock shaft or verge whereby said support will be alternately actuated to develop and relieve pressure upon said bar.

11. A cinematograph target embodying 100 therein a back plate comprising a plurality of independently movable sections, a plurality of independently movable frames, a screen carried by each of said frames, means whereby lineal traverse is imparted to said frames successively, controlling means for 105 said last named means adapted to be operated by the movement of any of said sections of said back plate to release said last named means to impart movement to said frames, comprising an escapement wheel included in the means for imparting movement to said frames, an oscillatory rock shaft or verge, a pallet carried thereby and operatively engaging said escapement wheel, 110 and operative connections between said verge and each of the sections of said back plate, and a brake mechanism operative upon said 115 rock shaft or verge comprising a reciprocatory bar operatively connected with said rock shaft or verge, a plurality of rollers disposed on opposite sides of said bar, a movable support for one of said rollers, means actuated from said rock shaft or 120 verge whereby said support will be alter- 125 nately actuated to develop and relieve pressure upon said bar.

nately actuated to develop and relieve pressure upon said bar, and manually operative means whereby the breaking action of said rollers upon said bar may be regulated.

5 12. A cinematograph target embodying therein a back plate comprising a plurality of independently movable sections, a plurality of independently movable frames, a screen carried by each of said frames, means whereby lineal traverse is imparted to said frames successively, controlling means for said last named means adapted to be operated by the movement of any of said sections of said back plate to release said last named means to impart movement to said frames, comprising an escapement wheel included in the means for imparting movement to said frames, an oscillatory rock shaft or verge, a pallet carried thereby and operatively engaging said escapement wheel, and operative connections between said verge and each of the sections of said back plate, and a brake mechanism operative upon said rock shaft or verge comprising 25 a reciprocatory bar operatively connected with said rock shaft or verge, a plurality of rollers disposed on opposite sides of said bar, a movable support for one of said rollers, means actuated from said rock shaft or verge whereby said support will be alternately actuated to develop and relieve pressure upon said bar, and manually operative means whereby the braking action of said rollers upon said bar may be regulated, consisting of a movable support for another of said rollers, a cam acting upon said support and means whereby said cam may be actuated.

13. A cinematograph target embodying therein a back plate comprising a plurality of independently movable sections, a plurality of independently movable frames, a screen carried by each of said frames, means whereby lineal traverse is imparted to said frames successively, controlling means for said last named means adapted to be operated by the movement of any of said sections of said back plate to release said last named means to impart movement to said frames, and a timing mechanism included in said means for imparting lineal traverse to said frames whereby said frames will be successively actuated and movement thereof immediately after the actuation of said controlling mechanism is avoided.

14. A cinematograph target embodying therein a back plate comprising a plurality of independently movable sections, a plurality of independently movable frames, a screen carried by each of said frames, means whereby lineal traverse is imparted to said frames successively, controlling means for said last named means adapted to be operated by the movement of any of said sections of said back plate to release said last

named means to impart movement to said frames, and a timing mechanism included in said means for imparting lineal traverse to said frames consisting of a plurality of ratchet wheels at each side of the target, connections between said ratchet wheels respectively and said frames respectively, a plurality of pawls adapted to coöperate with said ratchet wheels respectively and actuating means for said pawls whereby said pawls will be successively actuated and each of them will be caused to be only intermittently operative upon its ratchet wheel, whereby said frames will be successively actuated and movement thereof immediately after the actuation of said controlling mechanism is avoided.

15. A cinematograph target embodying therein a back plate comprising a plurality of independently movable sections, a plurality of independently movable frames, a screen carried by each of said frames, means whereby lineal traverse is imparted to said frames successively, controlling means for said last named means adapted to be operated by the movement of any of said sections of said back plate to release said last named means to impart movement to said frames, and a timing mechanism included in said means for imparting lineal traverse to said frames consisting of a plurality of ratchet wheels at each side of the target, connections between said ratchet wheels respectively and said frames respectively, a plurality of pawls adapted to coöperate with said ratchet wheels respectively, actuating means for said pawls whereby said pawls will be successively actuated and each of them will be caused to be only intermittently operative upon its ratchet wheel, whereby said frames will be successively actuated and movement thereof immediately after the actuation of said controlling mechanism is avoided, and means whereby each of said pawls is prevented from operatively engaging its ratchet wheel during the initial movement of the actuating means therefor.

16. A cinematograph target embodying therein a back plate comprising a plurality of independently movable sections, a plurality of independently movable frames, a screen carried by each of said frames, means whereby lineal traverse is imparted to said frames successively, controlling means for said last named means adapted to be operated by the movement of any of said sections of said back plate to release said last named means to impart movement to said frames, and a timing mechanism included in said means for imparting lineal traverse to said frames consisting of a plurality of ratchet wheels at each side of the target, connections between said ratchet wheels respectively and said frames respectively, a plurality of double acting pawl mechanisms adapted to co-

- operate with said ratchet wheels respectively, actuating means for said pawl mechanism whereby they will be successively actuated and each of them will be caused to be only intermittently operative upon its ratchet wheel, whereby said frames will be successively actuated and movement thereof immediately after the actuation of said controlling mechanism is avoided, and a reversing mechanism operatively connected with said pawl mechanisms whereby said pawl mechanisms will be actuated at predetermined intervals to change the direction of movement of the frames.
- 15 17. A cinematograph target embodying therein a back plate comprising a plurality of independently movable sections, a plurality of independently movable frames, a screen carried by each of said frames, means whereby lineal traverse is imparted to said frames successively, controlling means for 70 said last named means adapted to be operated by the movement of any of said sections of said back plate to release said last named means to impart movement to said frames, and a timing mechanism included in 75 said means for imparting lineal traverse to said frames consisting of a plurality of ratchet wheels at each side of the target, connections between said ratchet wheels respectively and said frames respectively, a plurality of double acting pawl mechanisms adapted to coöperate with said ratchet wheels respectively, actuating means for said pawls whereby said pawls will be successively actuated and each of them will be 80 caused to be only intermittently operative upon its ratchet wheel, whereby said frames will be successively actuated and movement thereof immediately after the actuation of said controlling mechanism is avoided, and a reversing mechanism operatively connected with said pawl mechanisms whereby said pawl mechanism will be actuated at predetermined intervals to change the direction of movement of the frame, consisting of parallel levers mounted upon said frames respectively, a guide frame pivotally mounted in the corresponding arms of said levers, a latch mechanism carried by each of said levers and the supporting means therefor, a 90 traveling block slidably mounted adjacent said frame, a tie-rod connecting said levers, blocks adjacent the opposite ends of said tie-rod, springs encircling said tie rod and acting between said block respectively and said 95 traveling block, stops limiting the movement of said traveling block whereby said springs will be tensioned during the movement of said levers in either direction, trip rods carried by said block adapted to coöperate with 100 said latches respectively whereby either of said springs after being tensioned will be automatically released to impart movement to said guide frame toward or from the movable frame carrying same, and a link movably mounted in said guide and connected with said double acting pawl mechanism whereby either pawl thereof may be brought into the operative relation to its ratchet.
- 10 15. A cinematograph target embodying 110 therein a back plate comprising a plurality of independently movable sections, a plurality of independently movable frames, a screen carried by each of said frames, means whereby lineal traverse is imparted to said frames successively, controlling means for said last named means adapted to be operated by the movement of any of said sections of said back plate to release said last named means to impart movement to said frames,
- 15 18. A cinematograph target embodying 120 therein a back plate comprising a plurality of independently movable sections, a plurality of independently movable frames, a screen carried by each of said frames, means whereby lineal traverse is imparted to said frames successively, controlling means for said last named means adapted to be operated by the movement of any of said sections of said back plate to release said last named means to impart movement to said frames,
- 20 185 19. A cinematograph target embodying 125 therein a back plate comprising a plurality of independently movable sections, a plurality of independently movable frames, a screen carried by each of said frames, means whereby lineal traverse is imparted to said frames successively, controlling means for said last named means adapted to be operated by the movement of any of said sections of said back plate to release said last named means to impart movement to said frames,

comprising an escapement wheel included in the means for imparting movement to said frames, an oscillatory rock shaft or verge, a pallet carried thereby and operatively engaging said escapement wheel, and operative connections between said verge and each of the sections of said back plate, and means for stopping the projector substantially simultaneously with the impact of a bullet 5 with any back plate section consisting of a fixed contact adjacent said rock shaft or verge, an arm carrying an opposed contact loosely mounted upon said rock shaft or verge, an arm carried by and movable with 10 said rock shaft or verge, a spring acted upon by said last named arm and acting upon the support for said movable contact, and a rigid member carried by said movable arm and extending through said support where- 15 by movement of said arm independently of 20 said support in one direction is permitted, said rigid member being provided with projections engaging said support whereby toward the limit of the movement of said arm 25 in the other direction said support will be actuated to separate said contacts.

20. A cinematograph target embodying therein a movable back plate, a plurality of parallel screen sections means whereby relative movement is imparted to said sections to obscure bullet openings therethrough, controlling means for said last named means adapted to be actuated by the movement of said back plate including therein a rock 30 shaft, operative connections between said rock shaft and said back plate and means for stopping the projector substantially simultaneously with the impact of the bullet with said back plate consisting of a movable contact and yieldable connections between said movable contact and said rock shaft whereby said rock shaft may have movement after the making of the contact.

21. A cinematograph target embodying 45 therein a back plate comprising a plurality of overlapping plates mounted upon a frame, suspension bars pivotally connected with said frame rearwardly of said plate whereby a normal backward thrust is exerted by said plates, a rock shaft common to 50 a plurality of said plates having crank arms thereon engaging said frames respectively, and another crank arm, a vertically extending rod operatively connected with said last named crank arm, a rock shaft or verge operatively connected with said vertically movable rods, a plurality of independently movable frames, a screen carried by each of said frames, means whereby lineal traverse is im- 55 parted to said frames successively and operative connections between said last named means and said rock shaft or verge.

22. A cinematograph target embodying 60 therein a movable back plate structure, a plurality of independently movable frames, 65

a screen carried by each of said frames, means whereby lineal traverse is imparted to said frames successively and controlling means for said last named means adapted to be actuated by the movement of said back 70 plate to release said last named means to impart movement to said frame.

23. A cinematograph target embodying therein a movable back plate structure, a plurality of independently movable frames, 75 a screen carried by each of said frames, means whereby lineal traverse is imparted to said frames successively, controlling means for said last named means adapted to be actuated by the movement of said 80 back plate to release said last named means to impart movement to said frame, and means actuated by the said controlling means for stopping the projector substantially simultaneously with the impact of 85 the bullet with said back plate.

24. A cinematograph target embodying therein a movable back plate structure, a plurality of independently movable frames, 90 a screen carried by each of said frames, means whereby lineal traverse is imparted to said frames successively, an automatically acting reversing mechanism whereby the direction of said traverse will be varied at predetermined intervals and 95 controlling means for said last named means adapted to be actuated by the movement of said back plate to release said last named means to impart movement to said frame. 100

25. A cinematograph target embodying therein a movable back plate structure, a plurality of independently movable frames, 105 a screen carried by each of said frames, means whereby lineal traverse is imparted to said frames successively, means whereby lateral movement is imparted to said screens during said lineal traverse, and controlling means for said last named means adapted to be actuated by the movement of said back 110 plate to release said last named means to impart movement to said frame.

26. A cinematograph target embodying therein a movable back plate structure, a plurality of independently movable frames, 115 a paper supply reel and a re-winding reel carried by each of said frames, means whereby said re-winding reel is automatically actuated at predetermined intervals, means whereby lineal traverse is imparted to said 120 frames successively and controlling means for said last named means adapted to be actuated by the movement of said back plate to release said last named means to impart movement to said frame. 125

27. A cinematograph target embodying therein a movable back plate structure, a plurality of independently movable frames, a paper supply reel and a re-winding reel carried by each of said frames, means where- 130

by said re-winding reel is automatically actuated at predetermined intervals, means whereby lineal traverse is imparted to said frames successively, means whereby lateral 5 movement is imparted to said screens during said lineal traverse, and controlling means for said last named means adapted to be actuated by the movement of said back plate to release said last named means to impart 10 movement to said frame.

28. A cinematograph target embodying therein a plurality of independently movable frames, a screen carried by each of said frames, means whereby lineal traverse is 15 imparted to said frames successively, controlling means for said last named means, and means whereby said controlling means may be actuated substantially simultaneously with the impact of a bullet with said 20 screens.

29. A cinematograph target embodying therein a plurality of independently movable frames, a screen carried by each of said frames, means whereby lineal traverse is 25 imparted to said frames successively, controlling means for said last named means, means whereby said controlling means may be actuated substantially simultaneously with the impact of a bullet with said screens, 30 and means actuated by said controlling means for stopping the projector substantially simultaneously with the impact of the bullet with said screens.

30. A cinematograph target embodying 35 therein a plurality of independently movable frames, a screen carried by each of said frames, means whereby lineal traverse is imparted to said frames successively, an automatically acting reversing mechanism 40 whereby the direction of said traverse will be varied at predetermined intervals, controlling means for said last named means, and means whereby said controlling means may be actuated substantially simultaneously 45 with the impact of a bullet with said screens.

31. A cinematograph target embodying therein a plurality of independently movable frames, a screen carried by each of said frames, means whereby lineal traverse is 50 imparted to said frames successively, means whereby lateral movement is imparted to said screen during said lineal traverse, controlling means for said last named means, and means whereby said controlling means may 55 be actuated substantially simultaneously with the impact of a bullet with said screens.

32. A cinematograph target embodying therein a plurality of independently movable frames, a paper supply reel and a re-winding reel carried by each of said frames, 60 means whereby said re-winding reel is automatically actuated at predetermined intervals, means whereby lineal traverse is imparted to said frames successively, controlling 65 means for said last named means and means adapted to actuate said controlling means substantially simultaneously with the impact of a bullet with said screen.

33. A cinematograph target embodying 70 therein a plurality of independently movable frames, a paper supply reel and a re-winding reel carried by each of said frames, means whereby said re-winding reel is automatically actuated at predetermined intervals, 75 means whereby lineal traverse is imparted to said frames successively, means whereby lateral movement is imparted to said screens during said lineal traverse, controlling means for said last named means 80 and means adapted to actuate said controlling means substantially simultaneously with the impact of a bullet with said screen.

In witness whereof, I hereunto affix my signature in the presence of two subscribing 85 witnesses, this 29th day of September, 1917.

HENRY B. THOMPSON.
